UNITED STATES PATENT OFFICE.

WILLIAM JACOB SALLY, OF OAKLAND, MISSISSIPPI.

DESIGN FOR A DESK.

No. 39,543.

Specification for Design.

Patented Sept. 15, 1908.

Application filed June 3, 1908. Serial No. 436,492. Term of patent 14 years.

To all whom it may concern:

Be it known that I, WILLIAM J. SALLY, a citizen of the United States, residing at Oakland, in the county of Yalobusha and State of Mississippi, have invented a new, original, and ornamental Design for Desks, of which the following is a specification, reference being had to the accompanying drawing, forming part thereof.

The figure is a perspective view of a desk, showing my new design.

I claim:

The ornamental design for a desk, as shown.

WILLIAM JACOB ^{his} ~~X~~ SALLY.
